US00D580885S

(12) **United States Design Patent**
Detering

(10) **Patent No.:** **US D580,885 S**
(45) **Date of Patent:** **** Nov. 18, 2008**

(54) **CONNECTOR MODULE FOR AN
OPTOELECTRONIC SENSOR**

(75) Inventor: **Frank Detering**, Stuttgart (DE)

(73) Assignee: **Sick AG**, Waldkirch (DE)

(**) Term: **14 Years**

(21) Appl. No.: **29/286,544**

(22) Filed: **May 9, 2007**

(57) **CLAIM**

The ornamental design for a connector module for an optoelectronic sensor, as shown.

DESCRIPTION

FIG. 1 is perspective view of the connector module for an optoelectronic sensor showing my new design;

FIG. 2 is a top plan view thereof;

FIG. 3 is a left side elevation view thereof;

FIG. 4 is a right side elevation view thereof;

FIG. 5 is a rear elevation view thereof;

FIG. 6 is a rear elevation view thereof; and,

FIG. 7 is a bottom plan view thereof.
